(57) **CLAIM**

The ornamental design for a rotary organizer, as shown and described.

DESCRIPTION

FIG. 1 is a front perspective view of a rotary organizer showing the new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines showing the bottom surfaces in FIGS. 7 and 8 are included from the purpose of showing portions of the rotary organizer that form no part of the claimed design:

1 Claim, 8 Drawing Sheets*FIG. 1*

FIG. 2

FIG. 3

FIG. 4

FIG. 5

FIG. 6

FIG. 7

FIG. 8
